UNITED STATES PATENT OFFICE.

RICHARD W. MILLER, OF RUTHERFORD, NEW JERSEY, ASSIGNOR TO THE MEYER-SNIFFEN COMPANY, LIMITED, OF NEW YORK, N. Y.

DESIGN FOR A LAVATORY-BRACKET.

SPECIFICATION forming part of Design No. 22,387, dated May 2, 1893.

Application filed December 29, 1892. Serial No. 456,706. Term of patent 14 years.

To all whom it may concern:

Be it known that I, RICHARD W. MILLER, a citizen of the United States, and a resident of Rutherford, in the county of Bergen and State of New Jersey, have invented a certain new and useful Design for a Lavatory-Bracket, of which the following is a specification.

In the accompanying drawing is shown in side elevation a lavatory bracket involving my novel design.

The main feature of my design consists in the quadrantal shape of the bracket. The general configuration of the bracket is quadrantal, and is formed by the horizontal bar or

member 3, the vertical bar or member 4, and 15 the arc-shaped bar or member 5, all joined together by globes or couplings 6.

What I claim is—

The quadrantal design of lavatory bracket, substantially as herein shown and described. 20

Signed at New York city, in the county of New York and State of New York, this 27th day of December, A. D. 1892.

RICHARD W. MILLER.
